CLOSURE DEVICE

Heinrich Quittner, Vienna, Austria

Application June 25, 1934, Serial No. 732,367
In Austria July 12, 1933

1 Claim. (Cl. 221—60)

I have filed applications in Austria on the 12th July 1933 and in Germany on the 29th January 1934, of which the following is a specification.

This invention relates to a new and improved closure device for collapsible tubes. Closure devices are already known for this purpose which consist of a closure member pivoted by means of a stirrup-shaped element on the neck portion or cap of the tube, and adapted to yield resiliently on passing over the rim of the orifice of the tube with a view to obtaining a snap engagement of the closure member over the orifice.

The production of closure devices of this type necessitates a high degree of accuracy in the dimensioning of the closure member and in the mounting of the stirrup-shaped holding element on the neck or cap portion of the tube, since the resilient deformation of the closure member on passing over the rim of the orifice must be of a certain magnitude to ensure satisfactory closure, but at the same time may not exceed a certain amount since otherwise the operation of the device is apt to require too much force and consequently to be attended by deformation of the tube and loss of the substance contained in the tube.

According to the present invention these drawbacks are obviated by mounting a snap closure member on the middle re-entrant portion of a dual link or pivoted holding element. The free ends of the outer limbs of this holding element are pivoted to the neck or cap portion of the tube, and the loops formed between these outer limbs and the re-entrant middle portion (on which the closure member is mounted) constitute wings for engagement by the thumb or finger in operating the device. It will thus be clear that when the device is swung up into the position of closure the re-entrant middle portion of the holder will become deformed relatively to the remainder of the holder, when the closure member encounters the rim of the orifice of the tube, by a couple of forces composed in the first place of the force applied to the holder, and in the second place of the resistance offered to the closure member at the rim of the tube orifice.

Constructional examples embodying the invention are shown in the accompanying drawing, in which:

Fig. 1 is a vertical section of a closure device according to the present invention.

Fig. 2 shows this same device in elevation.

Fig. 3 shows the same device in vertical section, but in the open position, while the two previous views show the same in the position of closure.

Figs. 4 and 5 show, in section and in elevation, respectively, a modified form of construction of the closure device according to the invention.

Figs. 6 and 7 show a further modification in sectional elevation.

Referring to Fig. 1, 1 denotes the threaded neck portion of a tube 2 on to which there is screwed a cap 3 with a central bore 4 (preferably of longitudinal cross-section). 5 denotes the side limbs of the dual link holder according to the invention the re-entrant middle portion 6 of which carries the closure member 7 which may consist for example of a small rubber sleeve. The portions of the holder between the re-entrant middle portion 6 and the side limbs 5 are formed into loops 8 which serve as wings for engagement by the thumb or finger in operating the device. The free ends 9 of the side limbs 5 are bent over into engagement with depressions 10 in the cap 3, for the pivotal mounting of the device.

In order to close the tube the procedure is as follows: The holder is grasped or otherwise engaged by one or both of the loops 8 and swung up from the open position (shown in Fig. 3) as indicated by the arrow on the extreme right in this figure. As soon as the rubber sleeve 7, in consequence of its distance from the pivot axis 10, encounters the rim *a* of the orifice of the cap 3 and is required to ride thereover the operating force *P* constitutes together with the resistance *R* offered by this rim to the closure member a force couple which first deforms the re-entrant middle portion of the holder, which is made of suitably resilient material, as indicated in chain-dotted lines in Fig. 3, and thus aids the resilient deformation of the closure member itself, and permits the same to ride over the rim of the orifice into snapping engagement with the latter very easily and with the application of but very slight force. As soon as the closure member rides over the orifice rim into the position of closure both the re-entrant middle portion of the holder and the closure member proper instantly resume their original position and condition, respectively (see Fig. 1), so that an effective and reliable seal is obtained.

If the outlet orifice 4 of the tube be of very small dimensions it may be sufficient to provide a closure device of the type shown in Figs. 4 and 5. The type of construction shown in these figures is substantially similar to that shown in Figs. 1 to 3, only that the web 6^a of the re-entrant middle portion of the holder itself serves, without any additional rubber sleeve, as the closure member proper.

5 In the form of construction shown in Fig. 6 the closure member 1 is provided on a wire stirrup or link 20 resiliently associated with a pivoted holder 21 preferably made of composition material. On the swinging of the holder 21 the wire link 20 is resiliently deformed in the manner described in connection with Fig. 3, with the same effect.

10 In the modified form shown in Fig. 7 the resilient carrying member 22 for the closure member is substantially straight and bridges the aperture in the holder 21.

15 Without departing from the scope of the invention the closure device can be mounted directly on the tube neck, as shown in Figs. 6 and 7. It is also possible to fit a substantially flat casing or envelope made of sheet metal, composition material, or the like, over the holder when formed in one piece with the carrying member as shown in Figs. 1 to 5. In this case sufficient 20 play must be provided between such casing or envelope and the carrying member to permit of the required resilient yielding movement of the latter.

It is also possible, by slight modification, to adapt all the described forms of construction of the closure device according to the invention for use in connection with bottles and other similar containers.

5 I claim:

A tube closure adapted for attachment to the tube neck to open and close the outlet through the neck comprising a closure cap capable of being screwed on the tube neck and provided with an outlet corresponding with the tube outlet, a resilient stirrup preferably of wire, the web of which carries a resiliently deformable closure body for the outlet in the closure cap and is provided with two upwardly projecting parts, each part being firmly connected at the end with an arm, these two arms being extended downwardly below the closure body and provided on their lower ends with short pins adapted to engage corresponding recesses on opposite points of the closure cap for pivotally mounting the closure device on the closure cap.
